UNITED STATES PATENT OFFICE.

CHARLES F. OVERLY, OF PITTSBURGH, PENNSYLVANIA, ASSIGNOR TO THE LAGONDA MANUFACTURING COMPANY, OF SPRINGFIELD, OHIO, A CORPORATION OF OHIO.

STRAINER.

1,102,791.

Specification of Letters Patent.

Patented July 7, 1914.

Application filed November 11, 1910. Serial No. 591,759.

To all whom it may concern:

Be it known that I, CHARLES F. OVERLY, a citizen of the United States, residing at Pittsburgh, in the county of Allegheny and 5 State of Pennsylvania, have invented certain new and useful Improvements in Strainers, of which the following is a specification, reference being had therein to the accompanying drawings.

10 My invention relates to strainers.

The object of my invention is to provide a strainer adapted to be cleaned while in operation or under pressure.

With this end in view I have devised a 15 strainer with a stationary strainer element therein and a cleaning chamber adapted to be cut off from the flow of the fluid; with means to clean the straining element while in its stationary position; and an access 20 opening to the cleaning chamber whereby the refuse matter may be removed; a closure for said opening; also a cock or valve whereby sediment and the like may be discharged without removing said closure.

25 With these and other objects in view my invention consists of the constructions and combinations hereinafter described and set forth in the claims.

In the accompanying drawing 1 represents a casing having an inlet 2 and outlet 3 with flanges as shown adapted to be connected in a pipe line. Said casing is provided with a removable cover 1^a and partition walls 1^b forming an inlet passage 4, a 35 straining chamber 5 and a cleaning chamber 6 open at the bottom to give access for cleaning and having a closure 7 removably secured in place by bolts 8. The straining element which I have shown in the form of a 40 perforated cylinder 9 extends from an opening 10 in the upper wall of said straining chamber to an opening 11 in the lower wall thereof, the lower end of said cylinder having a flange 12 resting in an annular recess 45 of a ring 13; said ring resting in an annular recess in the wall 1^b. The upper end of said cylinder is provided with a flange 14 secured to the partition wall 1^b by bolts 15.

A spindle 16 screw-threaded as shown extends through an opening in the cover 1^a and rests at its lower end in a step-box 17; said step-box being supported by a bridge-tree 1^c. The opening in the cover 1^a through which the spindle extends is provided with

a stuffing box 18; and a collar 19 fixed on the 55 spindle holds the spindle in place.

A valve 20 having a screw-threaded opening conforming with the screw-threads of the spindle 16 is provided with another opening 21 through which a guide or stop 60 22 extends to keep it from turning on the spindle, so that in operating the spindle in one direction by means of the hand-wheel 23 the valve will be moved from its position in the upper portion of the inlet passage 4 as 65 shown in the drawing to a seat 24 in the ring 13, thereby cutting off the cleaning chamber.

I preferably place the strainer with the cleaning chamber at the bottom so that the 70 refuse matter caught by the straining element will drop to said chamber; but the valve 20 is made of slightly less diameter than the inner diameter of the cylinder so that in its movement through the cylinder 75 such of the refuse matter as still clings to the chamber will be forced into the cleaning chamber. When the valve is in its seat, the closure 7 can be removed and the refuse matter in the cleaning chamber taken away. 80 The closure is then secured in place and the spindle operated to move the valve to its original position shown in the drawing. The valve 20 and its seat 24 I preferably 85 bevel as shown; and I further provide a nut 25 secured at the lower end of the screw-threads of the spindle; said nut having a beveled edge 26 adapted to fit a beveled annular groove 27 in the valve, so that when the valve comes to its seat the beveled edge 90 of this nut will also be seated in said beveled annular groove and prevent leakage through the valve. The guide or stop 22 is screw-threaded at its lower end into the bridge-tree and is held in place at its upper end by 95 extending into a recess 28 in the cover 1^a as shown.

I further preferably provide perforations 29 in the upper wall of the straining chamber to permit the flow of the fluid while the 100 valve is passing the upper flange of the perforated cylinder, and any refuse matter caught will be washed into the upper end and through the cylinder after the valve has passed said flange and returned to its 105 position in the upper portion of the inlet passage. A cock or valve 30 is provided which may be opened without removing the

closure 7 and while the cleaning chamber is under pressure or not as desired. By removing the cover 1^a the perforated cylinder can be taken out for renewal or repairs.

5 Having thus described my invention I claim:

1. In a strainer, a casing having a straining and a cleaning chamber and an inlet passage opening to said straining chamber, 10 two strainer elements, means to clean one of said elements, said means being operative from said inlet passage to an opening from said straining to said cleaning chamber and arranged to close said opening, the other 15 strainer element affording a passage for the fluid when said means is passing from said inlet to the straining chamber, substantially as described.

2. In a strainer adapted to be connected in 20 a pipe line to remove foreign matter from liquid being transmitted under pressure without interrupting the flow thereof, the combination of a casing having partitions forming an inlet and outlet and a straining and 25 a cleaning chamber, said cleaning chamber having an access opening with a closure for same, a cylindrical strainer element in said straining chamber extending from an opening from said inlet to an opening to said 30 cleaning chamber, a valve movable from said inlet through said strainer to close the opening to said cleaning chamber when the closure for said access opening is removed; the partition between said inlet and straining 35 chamber having perforations to pass and strain the liquid while the valve is passing through the opening in said partition, substantially as described.

3. In a strainer adapted to be connected in 40 a pipe line to remove foreign matter from

liquid being transmitted under pressure without interrupting the flow thereof, the combination of a vertical casing with horizontally extending inlet and outlet adapted to be connected in a pipe line and having 45 partitions forming an inlet passage, a straining chamber and a cleaning chamber, said inlet, outlet and partitions being formed integrally with said casing, a removable cover for said casing adapted to connect said passage with an opening to said straining chamber, a stationary cylindrical strainer element extending from said opening to an opening in said cleaning chamber, a valve adapted to pass through said strainer element from 50 the inlet passage to close the opening to said cleaning chamber, the partition between said inlet passage and straining chamber having perforations therethrough and said cleaning chamber having an access opening 55 with a closure for same, substantially as described.

4. In a strainer, the combination of a casing with an inlet and outlet and having partitions forming a straining and a cleaning 60 chamber with an opening from said straining chamber to said cleaning chamber, a valve and a spindle screw-threaded through an opening in said valve to operate the same to close said opening between the straining 65 and cleaning chamber, and means to prevent leakage through said screw-threaded opening in the valve, substantially as described.

In testimony whereof, I have hereunto affixed my signature in the presence of two 70 75 witnesses.

CHARLES F. OVERLY.
